UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

CONDENSING APPARATUS.

Application filed November 19, 1919. Serial No. 339,034.

To all whom it may concern:

Be it known that I, ROBERT SUCZEK, a citizen of the Czechoslovak Republic, residing in the city and county of Philadelphia, State of Pennsylvania, have invented certain new and useful Improvements in Condensing Apparatus, of which the following is a specification.

My invention relates to condensing apparatus comprising a condenser and ejector apparatus for maintaining therein a vacuum by withdrawing air and uncondensed vapors therefrom.

My invention resides in apparatus of the character hereinafter described and claimed.

For an illustration of some of the various forms my invention may take, reference is to be had to the accompanying drawings, in which:

Fig. 1 is a cross sectional view, partly in elevation, of combined condenser and air removing apparatus embodying one form of my invention.

Fig. 2 is a horizontal sectional view, partly in plan, taken on the line 2—2 of Fig. 1.

Fig. 3 is a vertical sectional view, partly in elevation, taken on the line 3—3 of Fig. 1.

Fig. 4 is a vertical sectional view, partly in elevation, of a form of my invention in which the condenser is of the jet type.

Fig. 5 is a horizontal sectional view, partly in plan, taken on the line 5—5 of Fig. 4.

Referring to Figs. 1 to 3 inclusive, C is the shell or body of a surface condenser wherein the cooling water is circulated through a plurality of tubes, not shown, while the condensable fluid, as steam from a turbine, engine or other source, entering at

1, passes through the interspaces between the tubes and is more or less completely condensed; the condensate passes by gravity into the hot well H, which is comprised in the condenser structure or unit, and is with-

45 drawn in known manner through the pipe 2. Within the condenser may be provided, as well understood in the art, a shield or baffle plate 3, the space between which and shell C is in free communication with the

50 steam or air space of the condenser. The air outlet 4 communicates with the space beneath the baffle 3 and with the pipe 5, controlled by valve 6, communicating with

the suction chamber 7 of an ejector E to whose nozzle structure 8 is delivered steam or other elastic condensable motive fluid which by known action is expanded by the nozzle structure 8 into jets which entrain the air in the chamber 7, thereby producing suction which removes air and uncondensed vapors from the condenser C to produce a vacuum therein. The mixture of motive fluid and entrained air is delivered into the diffuser 9 and discharged therefrom at higher pressure into the chamber 10 of the auxiliary or interstage condenser A. This condenser may be of any suitable structure and such, for example, as disclosed in my application Ser. No. 317,875, filed August 16, 1919. The chamber 10 is in the box or chest B divided by the walls or partitions 11 and 12 into three chambers, 10, 13 and 14, having a wall formed by the tube sheet 15 held between the member B and one end of the shell 16 of the condenser structure. Within the shell 16 are the downwardly extending plates or baffles 17 and 18 and the upwardly extending plate or baffle 19, these plates or baffles dividing the interior of the shell 16 into four passes, in which are disposed four groups of tubes 20 terminating in the tube sheet 15 and the lower tube sheet 21 held between the condenser shell 16 and the lower chest or box B¹. Cooling water enters at 22, flows downwardly between the tubes 20 around the lower end of baffle 18 upwardly through the second pass over the upper edge of the baffle 19, downwardly through the third pass and around the lower edge of the baffle 17 and upwardly through the fourth pass and out through the opening 23.

In the lower chest or box B¹ is the dividing partition or diaphragm 24 preventing equalization of pressure or other conditions as between the chambers 25 and 26, with the former of which communicate the lower ends of the first and second groups of tubes 20 and with the latter of which communicate the lower ends of the tubes 20 of the third and fourth groups.

With the chamber 14 communicates the pipe 27 delivering to the suction of a second stage pump of any suitable structure, here shown, however, as an ejector E¹ of the radial flow nozzle type having the discharge port 28.

Communicating with the chambers 25 and 26 are the pipes 29 and 30 controlled, respectively, by valves 31 and 32 and delivering into the pipe 33 which is formed into a 5 water seal structure which first extends downwardly, and then upwardly in the portion 33^a to a height 33^b above the lower ends of the pipes 29 and 30, and then communicates by the descending portion 33^c with the 10 portion 33^d delivering into the float box D forming part of the structure of the condenser unit, in the case illustrated forming part of the hot well structure H. A wall 34 is common to the hot well H and the box D, 15 the latter having the removable cover 35. In the wall 34 is a port 36 with which registers the hole 37 in the stationary cylindrical valve member 38 upon which is rotatable the cooperating valve member 39 having 20 ports 40 adapted to register with ports 41 in member 38 permanently in communication with the hole 37. To the movable valve member 39 is secured the arm structure 42 carrying at its outer end the float 43 resting 25 upon the condensate delivered into the box D through the pipe 33^d.

Communicating with the interior of the box D above the water level therein is the pipe 44 which at its other end communicates 30 with the chamber 14 or suction of the second stage pump or ejector E¹.

The operation is as follows:

Steam entering the condenser C at 1 is 35 condensed and flows as condensate into the hot well H and is withdrawn by pumps or otherwise through the pipe 2. Simultaneously the ejector E withdraws air and uncondensed vapors from the steam space of the condenser C producing a vacuum therein, 40 and the mixture of air and motive steam is discharged from the ejector E into the chamber 10, thence through the first group of tubes 20 into the chamber 25, thence upwardly through the second group of tubes 45 20 into the chamber 13, thence downwardly through the third group of tubes 20 into the chamber 26, and thence upwardly through the fourth group of tubes to the chamber 14, the steam being completely or substantially 50 completely condensed within the condenser tubes and falling as condensate into the chambers 25 and 26. The air delivered to the chamber 14 is at higher pressure than exists within the condenser C, and this pressure 55 may be further raised by any suitable pump or ejector E¹, the employment of the interstage condenser A relieving the second stage pump or ejector E¹ from compressing or raising to higher pressure steam as well 60 as air discharged by the first stage ejector E.

The condensate collecting in the chambers 25 and 26 flows through the pipes 29 and 30 into the pipe 33 and is delivered through the pipe 33^d into the box D, where it continues 65 to rise until such time as the float D is lifted,

rotating the movable valve member 39 in a counterclockwise direction, as viewed in Fig. 3, until the ports 40 and 41 come into register, as indicated in Fig. 3, whereupon the condensate from the interstage condenser 70 structure A which has been delivered into the box D is sucked through said ports from the box D through the hole 37 and port 36 into the condensate in the hot well H, since within the condenser C and above the water 75 or condensate in the hot well H the absolute pressure is less than in the box D, wherein the absolute pressure is approximately that on the discharge side of the ejector E and preferably at that point on the discharge side thereof at the remote end of the interstage condenser structure A.

By the U tube or equivalent structure of the pipe connection between the pipes 29 and 30 and the pipe 33^d condensate or water is always maintained in the lower ends of the pipes 29 and 30, whereby free communication between chambers 25 and 26 through pipes 29 and 30 is prevented; and this is desirable to prevent equalization of pressure 90 between chambers 25 and 26.

Referring to Figs. 4 and 5, my invention is shown embodied in condensing apparatus whereof the condenser is of the jet type. The condenser is indicated at J as comprising the annular injection water chamber 45 to which water is delivered through the inlet 46 and from which it is discharged through the annular series of nozzles 47 into direct contact with the incoming steam or other condensable fluid entering through the port 48, formed in a member 49 having the annular skirt or flange 50, with the space surrounding which the air connection is made with pipe 5 controlled by valve 6 and communicating with the ejector E with which is associated any suitable condensing structure, as A, described in connection with Fig. 1, and delivering, as in the case of Fig. 1, to any device or region, but preferably to a second stage pump or ejector E¹.

The pipes 29 and 30, as in Fig. 1, connect through pipe 33, sealing structure and pipe 33^d with the box D whose wall 34 constitutes also part of the wall of the body of the condenser J. The box D is closed by the cover 35, through which the pipe 33^d communicates with the interior of the box D. Within the box D is disposed float controlled valve structure such as described in connection with Fig. 1. A pipe 44 equalizes the pressure between the space above the condensate or water in the box D and the chamber 14 or any other suitable point beyond the discharge orifice of the first stage ejector E.

The operation is as follows:

The steam from a turbine, engine or any other suitable source enters at 48 and comes into direct contact with the injection water 130

delivered upwardly and inwardly by the nozzles 47 and is condensed thereby and falls therewith into the bottom of the body connection delivering condensed motive steam from said auxiliary condenser to said box.

J and is removed by a removal pump, not shown, whose rotary element is secured upon and driven by the shaft 52, having bearings 53, 53, as well understood in the art.

Simultaneously the ejector E withdraws air from the condenser J, maintaining a vacuum therein. The air and motive steam from the ejector E is discharged as in Fig. 1 into the chamber 10 of the interstage condensing structure, and the motive steam is condensed and delivered as before through pipes 29 and 30 through pipes 33 and 33^a into the box D, where the float rises with accumulation of condensate and opens the valve structure, whereupon the condensate is sucked into the condenser J and falls to the bottom in mixture with the condensed steam and injection water.

In both Figs. 1 and 4 the control by the float 43 is automatic in that when the level of the condensate is lowered by the suction of water into the hot well H or bottom of condenser shell J, the float falls restricting the coacting port areas, and when the level falls sufficiently, completely closing the valve until reaccumulation of condensate, which again raises the float and opens the valve.

The float and valve structure are so disposed that the valve structure is always, even at the lowest level of condensate in box D, completely submerged, so that the vacuum within the main condenser is not broken by passage of air backwardly through pipe 44 into box D and thence through the valve structure into the main condenser.

What I claim is:

1. The combination with a condenser unit comprising condensing structure and a condensate receptacle, of a steam actuated ejector removing air from said condenser, an auxiliary condenser condensing the motive steam discharged by said ejector, a box having a wall in common with the wall of said condensate receptacle, a port extending through said wall, valve structure controlling flow through said port, and a

connection delivering condensed motive steam from said auxiliary condenser to said box.

2. The combination with a condenser unit comprising condensing structure and a condensate receptacle, of a steam actuated ejector removing air from said condenser, an auxiliary condenser condensing the motive steam discharged by said ejector, a box having a wall in common with the wall of said condensate receptacle, a port extending through said wall, float controlled valve structure in said box controlling flow through said port, a connection delivering condensed motive steam from said auxiliary condenser to said box, and a pressure equalizing connection independent of said last named connection and extending between said box and the discharge of said ejector.

3. The combination with a surface condenser, of a hot well structure, a box, a wall common to said hot well and said box, a port in said wall, a valve structure controlling flow through said port, a float in said box controlling said valve structure, a steam actuated ejector for removing air from said condenser, an auxiliary condensing structure for condensing the motive steam from said ejector, and a connection for delivering the condensed motive steam to said box.

4. The combination with a condenser unit comprising condensing structure, a condensate receptacle, and a box on said receptacle having a ported wall in common with said receptacle, of valve structure controlling communication between said box and receptacle through the port in said wall, a float in said box controlling said valve structure, means for delivering liquid to said box, and means independent of said liquid-delivering means effecting communication between the space in said box above the liquid therein and a region whose pressure is below atmospheric pressure and above the pressure in said condenser.

In testimony whereof I have hereunto affixed my signature this 10th day of November, 1919.

ROBERT SUCZEK.
